TENTER MACHINE

Robert Marshall, Cranston, R. I.

Application July 21, 1936, Serial No. 91,700

10 Claims.

(Cl. 26—57)

This invention relates to improvements in tenter machines and the principal objects thereof are directed to the provision of means in a tenter chain to facilitate expansion or elongation of the rails of the machine.

A tenter machine includes spaced side rails on which the tenter chains run. Due to the fact that a tenter machine is usually operated in a heated room or enclosure, the rails tend to expand or elongate and when the temperature decreases, the rails contract. This contraction and expansion present a serious problem, and it is to overcome the difficulties brought about by the elongation or expansion of the rails that my invention relates.

Accordingly, I have devised novel means by which the rails may slide back and forth due to expansion or contraction while they may also be moved towards and away from one another for purposes of adjustment.

Various and numerous novel objects and advantages will be apparent from the following description of the invention in the form at present preferred, reference being had to the accompanying drawing wherein,

Fig. 1 is a side elevational view of a part of a side rail of a tenter machine, showing how it is associated with the supporting parts therefor;

Fig. 2 is an inverted plan view on the line 2—2 of Fig. 1;

Fig. 3 is a sectional elevational view on the line 3—3 of Fig. 1; and

Fig. 4 is a small scale diagrammatic plan view showing a part of the rails of a tenter machine.

Referring now to the drawing more in detail, the invention will be fully described.

A stand or support is represented at 2, there being one at either side of the machine. These stands or supports are secured to the floor or a foundation and a transverse or cross member 4, for convenience called a crosshead, is secured at its opposite end thereto. A supporting member, which may be called a saddle and indicated by 6, is slideable on a flange 8 of the cross member 4 at either end thereof. An adjusting shaft 10 is rotatable in suitable bearing members, such as 12 or the like, and extends through openings such as 14 in the saddles 6.

Nuts, such as 16, are on the shaft 10 and the said shaft and nuts are threaded as indicated. The nuts are carried in the saddle between suitable abutments such as 21. Usually, in a tenter machine there are a plurality of shafts such as 10 which are geared together to facilitate simultaneous rotation thereof. For the purpose of

explaining the present invention, it may be assumed that the shaft is squared as at 22, whereby it may be rotated by means of any suitable tool.

By rotating shaft 10, the saddles are moved toward and away from one another to facilitate adjustment of the rails whereby the tenter machine may accommodate various materials to be handled thereby.

A stud 24 projects upwardly from the upper side of the saddles 6, and saddlelinks 26 have lower and upper bored hubs 28 and 29 which receive the said stud 24. As the saddles 6 are moved back and forth, the saddlelinks are moved thereby. By reason of the studs 24 there may be some oscillating movement of the saddlelinks 26 relative to the saddles 6.

Rails, such as indicated by 30, rest on the saddlelinks 26. The rails may be of any length desired depending upon the length of the tenter machine. Where the machine is of relatively short length, there may be two or so rails on each side which are secured together. Where the machine is longer, there may be any number of rails suitably secured together at adjacent ends. In a machine where there are a number of rails, there are of course a greater number of the stands 2 and cross heads 4 so that the rails from end to end are suitably supported at intervals and may be adjusted at intervals.

The rails shown are adapted to support the outer and inner runs of the tenter chains. The rails 30 at their lower sides are provided with openings 34 through which the hubs 29 of the saddle 6 extend. It will be noticed that the said hub does not contact the openings 34 whereby the rail may move relative to the saddle.

Grooves or guideways extend longitudinally of the rails at each end of the opening 34 and blocks are slidably disposed therein. Bolts 40 extend upwardly through the saddlelinks and blocks 38, and the washers 42 are disposed over the transverse members 32 of the rails, with nuts 44 on the upper ends of the said bolts.

The washers tend to hold the rails on to the saddlelink while the blocks 38, being slidable in the slot 36, permit the rail to move longitudinally relative to the saddlelinks 26.

There may be certain finished pads on the upper part of the crosshead for the saddle to slide upon. Likewise, there may be certain finished pads on the underside of the rails and upper side of the saddlelinks to permit sliding of the rails along the saddlelinks, all as shown.

From the foregoing, it will be observed that the saddles are movable back and forth on the

crosshead for the purpose of moving the rails towards and away from one another. Therefore, the rails, and chains which they carry, can be located at different distances apart to meet various requirements.

With the construction described, the rails may expand or elongate and contract, they being slideable on the saddlelinks, while the blocks 38 and their guideways insure movements of the rails in 10 a definite path. Their elongation will not interfere with the sidewise adjustments thereof, and any elongation or contraction will not strain the parts since the rails are guided so as to be free to move longitudinally.

15 Various changes and modifications may be made in the form of the invention; therefore, I do not wish to be limited by the specific detail shown, but rather by the appended claims. What I desire to claim and secure by Letters Patent 20 of the United States is:

1. The combination in a tenter machine of a cross member, a support member slideable thereon in one direction, a third member pivoted thereto, a rail slideable on said third member, and means 25 associated with the rail and third member for guiding the rail for sliding movements substantially transverse to the direction of movement of the support member on the cross member, the said means including guideways in said rail and blocks on said third member slideable therein.

2. The combination in a tenter machine of a cross member, support members slideable thereon in a certain direction, means to simultaneously move said members towards and away from one 35 another, third members pivoted to said support members, rails slideable on said third members, and means associated with said rails and third members for guiding the rails for sliding movements in directions substantially transverse to the 40 direction of the movement of the support members, all adapted and arranged whereby the said rails may move relative to the support members in one direction and are moved towards and away from one another thereby.

45 3. The combination in a tenter machine of a cross member, support members slideable therein towards and away from one another, third members, pivotal connections between said support members and third members, rails slideable on said 50 third members, and guiding means associated with said third members and rail members permitting sliding movements of the rails on the third members substantially transverse to the movement of the supports towards and away from 55 one another.

60 4. The combination in a tenter machine of a cross member, support members slideable therein towards and away from one another, third members, pivotal connections between said support members and third members, rails slideable on said 65 third members, and guiding means associated with said third members and rail members permitting sliding movements of the rails on the third members substantially transverse to the movement of the supports towards and away from one another, the said guiding means being separate from the pivotal connections.

70 5. The combination in a tenter machine of a cross member, support members slideable therein towards and away from one another, third members, pivotal connections between said support

members and third members, rails slideable on said third members, guiding means associated with said third members and rail members permitting sliding movements of the rails on the third members substantially transverse to the movement of the supports towards and away from one another, the said guiding means being separate from the pivotal connections, and means preventing upward movements of the rails on the third members.

5 6. The combination in a tenter machine of a cross member, supports slideable therein towards and away from one another, means to move said supports towards and away from one another, third members on said supports, pivotal connections between said support members and third members, rail members slideable on said third members, guiding means associated with said third and rail members restricting movements of the rail members to movements substantially 10 transverse to the movements of the supports towards and away from one another, the said guiding means including guides in the form of slots.

15 7. The combination in a tenter machine of a cross member, supports slideable therein towards and away from one another, means to move said supports towards and away from one another, third members on said supports, pivotal connections between said support members and third members, rail members slideable on said third members, guiding means associated with said third and rail members restricting movements of the rail members to movements substantially 20 transverse to the movements of the supports towards and away from one another, and means preventing separation of said rail and third members.

25 8. The combination in a tenter machine of a cross member, supports slideable therein towards and away from one another, means to move said supports towards and away from one another, third members on said supports, pivotal connections between said support members and third members, rail members slideable on said 30 third members, guiding means associated with said third and rail members restricting movements of the rail members to movements substantially transverse to the movements of the supports towards and away from one another, and means preventing separation of said rail and third members.

35 9. The combination in a tenter machine of a cross member, supports slideable therein towards and away from one another, means to move said supports towards and away from one another, third members on said supports, pivotal connections between said support members and third members, rail members slideable on said 40 third members, guiding means associated with said third and rail members restricting movements of the rail members to movements substantially transverse to the movements of the supports towards and away from one another, the said guiding means including blocks pivotally associated with one of said members slideably receivable in slots provided in the other member.

45 10. The combination in a tenter machine of a cross member, supports thereon slideable towards and away from one another and relative thereto, rails freely slideable relative to said supports, and guiding means to restrict sliding movements of the rails substantially transversely to the movements of the supports including substantially 50 rectangular blocks having flat faces and guideways in the form of slots receiving said blocks.

55 11. The combination in a tenter machine of a cross member, a support member slideable thereon, a third member pivotally connected to the support member, a rail slideable on the third member, aligned guideways in the rail at either side of the said pivotal connection, and guides in the third member pivoted thereto and slideable in the guideways.

70 ROBERT MARSHALL.
